UNITED STATES PATENT OFFICE.

WILLIAM COCHRAN, OF PATERSON, NEW JERSEY.

JACQUARD-CARD-CUTTING MACHINE.

1,069,529.

Specification of Letters Patent.

Patented Aug. 5, 1913.

Application filed May 22, 1912. Serial No. 698,901.

To all whom it may concern:

Be it known that I, WILLIAM COCHRAN, a citizen of the United States, residing at Paterson, in the county of Passaic and State 5 of New Jersey, have invented certain new and useful Improvements in Jacquard-Card-Cutting Machines, of which the following is a specification.

This invention relates to the art of repeating 10 the patterns or designs represented by punched jacquard cards. The repeating operation as now practised results in the repeated cards being so far exact replicas of the master cards that if there are, for instance, sixty-four rows of units (perforations and blanks) in the length of the master card, each row having a length of ten units, the repeated card has also sixty-four rows, each of ten units. Quite often the fabric 15 manufacturer finds it expedient or necessary to put into operation jacquard machines adapted for cards of one size (or punched field or area) punched with the same design or pattern as is or is to be worked out in 20 cards of a different size capable of being used only in other jacquard machines. But this can only be done by having the design first worked out in a piano machine in cards of the desired or new punched field or area— 25 an operation which is tedious, slow and expensive and requires more or less highly skilled labor—and then repeated, using the cards thus produced as master cards in a repeating machine operating as above indicated. 30

The object of this invention, therefore, is to provide a machine whereby the repeating operation may be performed under conditions where the repeated cards are to have 40 any punched field or area, that is, either of the same width as, or wider or narrower than, the punched field or area of the master card or other piece.

In the accompanying drawings, I have 45 illustrated my invention by way of example in the preferred embodiment thereof, Figure 1 being a front elevation of the machine, with certain parts broken away; Fig. 2 a side elevation thereof, partly in section; Fig. 50 3 is a fragmentary side elevation, on a larger scale, showing the head in which are housed the punches and their abutment keys and also showing the card feeding means; Figs. 4 and 5 show a fragment of the said head, a

few of the punches and their abutment keys 55 with the head depressed and all of said punches operative in the one instance (Fig. 4) and only a part of them operative in the other instance (Fig. 5), Fig. 4 also showing a part of the means which controls the abutment keys; Fig. 6 shows several of the punches and, in section in a vertical plane on a crosswise line of the punches, certain parts in which the punches are guided; and Figs. 7 and 8 are plan views of a master strip or 60 piece having the design to be repeated and a blank card undergoing the repeating operation, certain punch guides *o* and *q* being also shown in plan.

The frame *a* has a bed *d* on which are arranged the adjustable guides *c* for the blanks *A*, which are to become the repeated cards. The blanks *A* are fed endwise over the bed *b* from front to rear by the clip *d* shown in Fig. 3, said clip being a part of a traveler *e* 75 which is normally drawn rearwardly by a weight *f* connected with the traveler by a cord or the like *g* extending over a pulley *h* arranged at the rear end of a horizontal guideway *i* on which the traveler slides. 80 An escapement mechanism, forming no part of this invention and which it is unnecessary to describe further than by indicating the part *j* to be a fixed rack, and *k* two pawls which coöperate with the rack and move 85 with the traveler, receiving an oscillating motion from the rock shaft *l* which is actuated through the connecting means *m* from the main rotary shaft *n*, is employed, the same causing the rearward movement of the 90 traveler, and hence of the blank card *A*, to be a step-by-step one.

On the bed *b* is arranged a guide *o* for the punches, the same being perforated for the reception of the punches, which is of course 95 true also of the bed *b* which thus forms a die. The head, *p*, includes the part *q*, for the reception of the punches, and the harped-shaped structure *r* whose inclined portion *s* is stepped on its under side as 100 shown and has a series of horizontal apertures forming guideways coinciding with the steps of said portion *s*. The punches *t* are arranged in the present instance in five crosswise rows or lines, there being sixteen 105 punches in a row. The part *q* of the head has five crosswise slots *u* formed with shoulders *v* and receiving the rows of punches

whose fixed collars *w* are held against the shoulders *v* by spiral springs *x* interposed between part *q* and collars *y* on the punches. The punches *t* are operative in working out the design; other punches *t'* yieldingly supported in substantially the same way as the punches *t* may serve for forming the holes in the cards whereby the latter are laced together. The head *p* is carried by two uprights *z* which slide in the bed *b* and brackets *2* and are rigidly connected by the cross-head *3* which is reciprocated from a crank *4* on the shaft *n* by a pitman *5*.

The apertures in the inclined or stepped portion *s* of the head *p* are arranged in five rows of sixteen apertures to a row. In them slide the abutment keys *6*, of which there is one for every punch *t*. The punches *t* are graduated in length (Fig. 1) and each is of such length that when its corresponding abutment key *6* overhangs the punch, being at that time moved inward to a limit afforded by a stop *7* on the key, the punch will be active, but when the key is withdrawn as shown in Fig. 5, the punch may recede on impact with the card being punched. This part of the machine is old and well-known. Each abutment *6* has an extension *8* pivoted thereto and in the present instance consisting of a wire. The several wires are guided in the grids *9* of a frame *10* which is secured to the side of the frame *a*, the openings in the grids for the reception of the wires being vertical slots *11*. The portions of the wires which are received in the grids are horizontal, while the portions thereof between the grids and the abutment keys are inclined downwardly, that is, by bending the wires; this results in the parts *6* and *8* being held against turning, preserving certain bends *12* in the wires, which form stops to engage the extreme left-hand grid, always projecting upwardly. Springs *13*, interposed between the extreme right-hand grid and fixed collars *14* on the wires *8* normally press the latter to the left in the drawings. Thus, as the head rises and falls, the abutment keys are normally held by the springs *13* at their inward limits of movement, that is, overhanging the punches.

The rendering of any punch inactive is accomplished by raising its extension *8*, when the head is at its highest elevation, until the stop *12* is in position to be opposed by the left-hand grid *9* against longitudinal left-hand movement; the extension being thus held against longitudinal movement, when the head descends the result will be to withdraw the abutment key out of overhanging relation to the punch. To accomplish the selective raising of the extensions I provide the vertical needles *15* each formed with an eye *16* loosely receiving one of the extensions. The needles *15* are guided

in the grids *17* of the frame *10*, being held by gravity with their collars *18* resting on the lower grid *17*. The needles are arranged in the present instance ten-in-a-row in eight crosswise rows.

19 is a vertically movable carrier having an arm *20* which penetrates and is suitably guided by a slot *21* in the side of the frame *a* and has a sleeve *22* loosely embracing one of the uprights *z*. By means of a pitman *23* the carrier is connected with a lever *24* which rests on a cam *25* on the shaft *n*, the carrier being supported by the cam through the medium of the parts *23* and *24*. The carrier has a perforated horizontal needle board *26* the holes in which correspond in number and disposition to the needles. The master strip *B* which is punched with the pattern or design to be repeated, is fed over the needle board from the supply drum *27*, journaled in the carrier and having a crank *28*, to a take-up roller *29*, also journaled in the carrier. To keep the strip *B* under tension, the drum *27* may be suitably adapted to offer resistance against rotation and the take-up roller may be influenced by a weight *30* to tend to rotate in the direction of the arrow in Fig. 2. The weight *30* is attached to one end of a cord *31* which is wound on a drum *32* pressed against the end of the take-up roller by a spring *33*, the abutting faces of the drum *32* and take-up roller being formed as ratchet clutch members *34*, as shown in Fig. 1. By this arrangement, when the weight has descended until the cord has nearly or quite unwound, the drum *32* may be rerotated independently of the take-up roller so as to rewind the cord.

35 is a guiding roller for the strip *B* arranged forward of the needle board. The strip *B* is formed with two lateral rows of perforations *36* (it being understood that the other perforations between these rows *36* constitute the design) with which engage the peripheral studs on a drum *37* revolvable in the carrier below the needle board and provided with a ratchet *38*. With this ratchet engages a pawl *39* which, on each rotation of shaft *n*, is actuated from a cam *40* on said shaft through the medium of a lever *41*.

42 is a perforated plate receiving the needles *15* and carried by the uprights *43* at such an elevation above the collars *18* on the needles that each time the carrier descends it will engage said collars and insure the return of the needles to their lowermost positions.

Operation: On each downward stroke of the head *p* the cam *40* engages the lever *41* and causes pawl *39* to advance the master strip *B* the required distance to bring the part of the design or pattern immediately following that last influencing the needles under the latter, this occurring when (lever *130*

24 being now depressed) the carrier is down and the strip B is thus clear of all of the needles. During the descent of the head *p* the plate 42 acts to reset such needles as were last raised in the selecting operation. Those punches which are backed by abutment keys of course operate at this time to perforate the card A, the rest yielding upwardly in the head *p*. On the rise of the head the following operations occur: The escapement mechanism shown in Fig. 3 produces the necessary increment of advance of the card A so as to bring it into position for the next punching operation. The cam 25 causes lever 24 to act through pitman 23 to raise the carrier. Strip B, now advanced to the new position, thus effects the raising of certain of the needles, leaving the rest unelevated, the raising of the extensions 8 appertaining to the needles thus raised bringing the stops of said extensions to the position indicated by the dotted outline in Fig. 4. On the now-ensuing downward movement of the head the abutment devices 6, 8 whose extension portions 8 are raised cannot move longitudinally or thrustwise relatively to frame 10 under the pressure of the springs 13 owing to their stops engaging the left hand grid in Fig. 4, so that as soon as the head descends they perform a (retreating) thrust-movement relatively to the head out of abutment relation to the punches; the rest partake on the other hand of thrust-movement relatively to frame 10 as, held by their springs to the left, their abutment-key-portions descend with the head. The cam 25 is so formed that it holds the carrier, when elevated, in a state of dwell of sufficient extent to maintain the locked-back condition of the called key-abutments until their punches have, by engaging the card, been pushed sufficiently upward in the head to prevent said abutment keys from slipping over them.

It will be understood that the relation of the selecting needles to the punches is variable, the order in which the needles are coupled with the extensions 8 being not fixed but capable of change by changing about the needle-eyes 16 with respect to the extensions or the abutment keys in their apertures, so that the machine may be adapted to master strips and cards to be punched whose punched fields or areas may vary. In the present instance, as stated there are 8 crosswise rows of selecting needles, 10 to a row, making 80 in all; there are 5 rows of punches, 16 to a row—80 in all. Counting from rear to front as to rows and from right to left in each row, the first punch is coordinated with the first needle, and so on throughout the two groups (punches and needles), as indicated by the numbers 1, 11, 21 etc. on the strip and card shown in Figs. 7 and 8 and on the punches in Fig. 8. The 65 groups of units separated by transverse dot-

and-dash lines in Fig. 8 and indicated by Roman numerals correspond to the groups of units similarly designated in Fig. 7.

It will be understood that by following this method of arranging the punches with reference to the selecting devices the extent of each row of punches may be varied as desired so as to change the width-gage of the repeated card, although the width-gage of the master strip remain constant; it being always necessary, however, that the last unit (number 80 in the present instance) of the repeated card occur at relatively the same side thereof as the last unit appears in the master strip. The method above indicated I have made the subject of my application filed May 15, 1912, Serial No. 697,439 and is not claimed herein.

In the repeating operation it may frequently be desired or necessary to repeat either a series of design- or pattern-sections I, II, III, etc., or any one of them. In such case, the strip B can be fed backward the desired distance by rerotating the supply drum 27 by means of handle 28.

Having thus fully described my invention, what I claim as new and desire to secure by Letters Patent is:—

1. In combination, the frame, a punching mechanism including a gang of punches, a gang of selecting devices controlling the punches, said devices being interchangeably coördinated with the punches, and means for feeding a punched pattern piece past and intermittently bringing the same against the selecting devices, substantially as described.

2. In combination, a punching mechanism including a punch-carrying member and a punch yieldingly arranged in said member, an abutment-device for the punch, a withholding member for the abutment-device, one of said members being movable relatively to the other substantially parallel with the punching-thrust line, and said device having a thrust-movement in both members crosswise of said line and normally held in abutment relation to the punch, said device being also movable in the withholding member crosswise of the line of thrust-movement of said device and having a stop to engage said withholding member, and means for moving said device crosswise of its line of thrust-movement, substantially as described.

3. In combination, a punching mechanism including a punch-carrying member and a punch yieldingly arranged in said member, an abutment-device for the punch, a withholding member for the abutment-device, one of said members being movable relatively to the other substantially parallel with the punching-thrust line, means for forcing said device into abutment relation to the punch, said device being also movable in the withholding member crosswise of the

line of thrust-movement of said device into abutment relation to the punch and having a stop to engage said withholding member, and means for moving said device crosswise of its line of thrust-movement, substantially as described.

4. In combination, a punching mechanism including a die, a punch-carrying member and a punch yieldingly arranged in said member, an abutment-device for the punch, a withholding means for the abutment-device, means for reciprocating the punch-carrying member relatively to said means, said device having a thrust movement in the punch-carrying member and also in said means crosswise of the line of thrust-movement of the punch-carrying member, means for forcing said device in one of the directions in which it has thrust-movement, said device being also movable in the withholding means crosswise of the line of thrust-movement of said device and having a stop to engage said withholding means; and means for moving said device crosswise of its line of thrust-movement, substantially as described.

5. In combination, a punching mechanism having a vertical thrust-movement and including a punch-carrying member and a punch arranged in and vertically yielding in said member, an abutment-key for the punch having thrust-movement in said member crosswise of the punch, a withholding means with reference to which said member is movable, an extension attached to said key, partaking of the thrust-movement thereof and arranged in said means, means for forcing said key and extension in one of the directions in which they have thrust movement, said extension having a stop to engage the withholding means and being movable crosswise of the line of thrust-movement of said extension, and means for moving said extension crosswise of its line of thrust-movement, substantially as described.

6. In combination, with the frame, a die arranged therein, a vertically movable punch-carrying member, a gang of punches carried by said member, a gang of selecting devices including vertically arranged and vertically movable needles respectively co-ordinated with said punches, a vertically movable carrier arranged in vertical alinement with the needles and having means to guide and support a punched pattern piece, a rotary drive shaft, means for transmitting reciprocating movement from said shaft to the punch-carrying member and means for transmitting reciprocating movement from said shaft to the carrier, substantially as described.

7. In combination, with the frame, a die arranged therein, a vertically movable punch-carrying member, a gang of punches carried by said member, a gang of selecting

devices including vertically arranged and vertically movable needles respectively co-ordinated with said punches, a vertically movable carrier arranged in vertical alinement with the needles and having means to 70 guide and support a punched pattern piece, a rotary drive shaft, means for transmitting reciprocating movement from said shaft to the punch-carrying member, means for transmitting reciprocating movement from 75 said shaft to the carrier, a rotary feed device for the pattern-piece arranged in the carrier, and means for rotating said feed device on movement of the carrier, substantially as described.

8. In combination, the frame, a punching mechanism including a gang of punches each arranged to yield in a line parallel with the punching-thrust line, abutment devices for the punches movable back and forth into and 80 out of abutment-affording relation to the punches and normally moved in one direction, means for holding said devices against movement including selecting devices for the abutment devices each also movable parallel with said punching-thrust line, a movable carrier for the punched pattern piece, and means for operating the punching mechanism and reciprocating the carrier, substantially as described.

9. In combination, the frame, a punching mechanism including a movable punch-carrying member, a plurality of punches carried by and yieldable in said member, a plurality of abutment-devices for the respective punches, 100 said abutment devices being movable in said member into and out of abutment relation to the punches and normally held in abutment relation thereto, and means, selectively operative on the abutment-devices, for holding them in substantially fixed relation to the frame during the movement of said member, substantially as described.

10. In combination, the frame, a punching mechanism including a movable punch-carrying member, a plurality of punches carried by and yieldable in said member, a plurality of abutment-devices for the respective punches, said abutment-devices being movable in said member into and out of abutment relation to the punches, and means, operative on each selecting device, for alternately holding the same in substantially fixed relation to the frame and releasing said device during the movement of said member, 115 substantially as described.

11. In combination, a punching mechanism including a punch-carrying member and a punch yieldingly arranged in said member, and mechanism for at times opposing the yielding of the punch including an abutment-device movable in said member into and out of the path of yielding movement of the punch, and means to which to secure said device substantially immovably, 125 130

said member and said means having movement the one relatively to the other, substantially as described.

12. In combination, a punching mechanism including a punch-carrying member and a punch yieldingly arranged in said member, and mechanism for at times opposing the yielding of the punch including an abutment-device movable in said member into and out of the path of yielding movement of the punch, and means to which to secure said device substantially immovably, said member and said means having movement the one relatively to the other substantially parallel with the punching thrust-line, substantially as described.

13. In combination, coacting supporting members one of which is movable relatively to the other, a punch yieldingly arranged in one of said members, an abutment device arranged in both members and movable therein back and forth into and out of abutment-affording relation to the punch, and means in the other member for controlling the movement of said abutment device in said members, substantially as described.

14. In combination, coacting supporting

members one of which is movable relatively to the other, a punch yieldingly arranged in one of said members, an abutment device arranged in both members and movable therein back and forth into and out of abutment-affording relation to the punch, and means in the other member for opposing the movement of said abutment device in one direction, substantially as described. 30 35

15. In combination, coacting supporting members one of which is movable relatively to the other, a punch yieldingly arranged in one of said members, an abutment device arranged in both members and movable therein back and forth into and out of abutment-affording relation to the punch and normally impelled in one direction, and means in the other member for opposing the movement of the abutment device in said direction, substantially as described. 40 45

In testimony whereof I affix my signature in presence of two witnesses.

WILLIAM COCHRAN.
